UNITED STATES PATENT OFFICE.

CHARLES E. GIERDING, OF NEWARK, NEW JERSEY.

FARE-REGISTER.

No. 834,119.

Specification of Letters Patent.

Patented Oct. 23, 1906.

Application filed March 15, 1906. Serial No. 306,268.

To all whom it may concern:

Be it known that I, CHARLES E. GIERDING, a citizen of the United States of America, and a resident of Newark, in the State of New Jersey, have invented a new and useful Improvement in Fare-Registers, of which the following is a specification.

This invention relates to what are known as "fare-registers," primarily designed for use on street-cars and like public conveyances; and it relates, primarily, to that class of such registers in which provision is made for printing the indications of the register, including the indication of its direction sign or indicator and for preserving a record of the same which is accessible to the proper officers, but not to the conductor, who is required to register the fares and otherwise to operate the register according to rule, including the operation of its printing device and the resetting of its trip-register numeral-wheels or equivalent trip-counters to zero at the end of each trip or at other predetermined times.

The leading object of the present invention is to put the operation of the trip-indication-printing device under the control of the trip-counter-resetting means, so that the printing device cannot be shifted without resetting the trip-counter to zero if there have been any registrations since the previous resetting operation, while provision is at the same time made for operating the impression-taking device and resetting the trip-counter as often as may be desired without shifting the printing device, or, in other words, as often as may be desired during each trip, this being required on roads operated on what is called the "zone" system, where there are several fare limits between termini.

Another object of the invention is to render the operation of the direction-indicator subject to the control of the resetting mechanism notwithstanding the adaptation of the latter to be operated independently, so that the direction-sign can only be changed during a resetting operation.

Another object is to indicate to the conductor the moment during which the direction-indicator and the trip-indication-printing device may be shifted to expose a different direction-sign and to correspondingly shift the printing device.

Other objects are to perform the several functions above indicated by strong and

simple devices that are not likely to get out of order and can be accommodated within very little space at one and the same side of the registering mechanism.

Three sheets of drawings accompany this specification as part thereof.

Figures 1 and 2 are respectively face and edge views of the register proper detached from the customary operating-back and exposing to view its external characteristics. Fig. 3 is a face view of the register, on a larger scale, with the front of the register-casing and the dial-plate removed. Figs. 4 and 5 are views of one and the same side of the internal mechanism exposed to view in Fig. 3 with the record-drum removed and the back of the register-casing in section, the moving parts of the resetting and printing devices being shown in the respective views at rest, Fig. 4, and with a resetting operation in progress, Fig. 5, and the parts by which the direction-indicator and trip-indication-printing device are shifted being shown in their respective positions of rest by full and dotted lines in Fig. 5. Fig. 6 is a like view of the lower part of the register with the parts in the foreground in Figs. 4 and 5 removed and broken away to expose the parts behind. Fig. 7 is a half back view of the record-drum detached. Fig. 8 is a face view, partly in section, showing the printing device in vertical section in planes substantially parallel to the back of the register and illustrating the operation of reversing or shifting the direction-indicator and the trip-indication-printing device; and Figs. 9 and 10 are respectively a fragmentary sectional bottom view and a fragmentary sectional side view illustrating a modification.

Like reference characters refer to like parts in all the figures.

The improved fare-register may be of any approved external appearance. In the form in which it is shown in the drawings its external characteristics (represented in Figs. 1 and 2) include a circular casing having a back part *a*, of cast-iron, a removable front part *b*, of sheet metal, and a circular glass front plate *c* and a dial-plate *d*, exposed to view by said front plate and provided with index-holes *e'*, *f'*, and *g'*, which expose to view, respectively, a set of trip-counter numeral-wheels *e*, a set of totalizer numeral-wheels *f*, and the direction sign or indicator *g*. An actuation-indicator *h*, Figs. 3 and 8, is also exposed to view through said index-hole *e'* in

front of the units-wheel of said trip-counter numeral-wheels *e* during each registering operation, and a not-set flag or indicator *i*, Figs. 3 and 8, is exposed to view through the 5 same index-hole during each resetting operation.

An inconspicuous sight-hole *j'*, Fig. 1, in the dial-plate *d* for the benefit of the conductor, exposes to view an indicator-spot *j*, Fig. 10 8, of a contrasting color on a movable part behind the same when the trip-counter-resetting operation has progressed to a sufficient extent to unlock the direction-indicator *g* and the trip-indication-printing device *k*. Other 15 external characteristics of the register include a rearwardly-projecting stud *l*, Figs. 2, 4, and 5, forming part of the actuating mechanism by which the registration of fares is effected, and the bell *m*, Figs. 3 and 8, 20 within the register-casing is rung to attest the registration of each fare, a protruding knob or attached key *n*, by which the resetting operation is effected and the printing device hereinafter described is operated, a 25 normally locked door *o'* affording access to the removable record-drum *o* of the printing device, and a protruding handle *p*, by which the direction-indicator *g* and printing device *k* are shifted under the control of the resetting means, as hereinafter set forth.

The internal mechanism will now be more particularly described, as illustrated by Figs. 3 to 8 inclusive, which see. Each time the register is "pulled" through the medium of 35 said rearwardly-protruding stud *l* motion is simultaneously transmitted from the latter to the units-wheels of the trip-counter wheels *e* and the totalizer-wheels *f* and to the units-wheel of a set of number-printing 40 wheels *k'*, associated with the printing device *k*. The actuation-indicator *h* is simultaneously moved into its effective position, and at the end of the registering operation the bell-hammer *m'*, Figs. 3 and 8, is actuated to ring 45 the bell *m*. The specific devices represented in the drawings, by which these several operations are effected, are or may be identical with those more particularly described in my specification forming part of an application 50 for United States Letters Patent filed the 13th day of January, 1906, Serial No. 295,932, and as their details form no part of the present invention further description thereof is omitted from the present specification. At 55 the end of each trip or travel in a given direction, or as often as may be desired, the trip-counter numeral-wheels *e* are reset to zero by pulling and turning the key *n*, and therewith a horizontal shaft *n'*, upon which said 60 trip-counter numeral-wheels rotate in the registering operation, by means of which motion is transmitted to the several wheels in the resetting operation and the protruding ends of which support, respectively, the bell 65 *m* and the record-drum *o*. The devices rep-

resented in the drawings by which said trip-counter numeral-wheels *e* are thus reset to zero and by which the resetting movements of said shaft *n'* are controlled, together with the means for actuating said not-set indicator *i*, and for simultaneously locking the mechanism against registering operations by means of a bolt *q*, Figs. 3 and 8, are or may be likewise identical with those described and referred to in said specification 75 forming part of said application for patent, Serial No. 295,932, and their details form no part of the present invention. Immediately preceding the completion of each resetting operation motion is transmitted by a cam *r* 80 on said shaft *n'* through a yoke *r'* embracing the same to a slidable frame *s*, in which said printing-wheels *k'* are mounted, on a shaft *k''*, that is geared to the units-wheel shaft *f''* of said totalizer-wheels *f*, as shown in Figs. 3 85 and 8, and which also carries the trip-indication-printing device *k* in the form of a type-block fast on said shaft *k''*, this shaft being loose within all the printing-wheels *k'* and extending therethrough to a butterfly-cam 90 *t*, exposed to view in Figs. 6 and 8. Said printing device *k* has two printing-surfaces 1 and 2, Figs. 4 and 5, one of which is adapted to print one of the indications or signs of the direction-indicator *g* and the other is preferably adapted to print the number of the individual-fare register, or a like arbitrary indication or symbol identifying the record with the particular register, or with the conductor in charge of the same. After taking 100 an impression from one or the other of said printing-surfaces 1 and 2 of the printing device *k*, in the position in which the surface 1 is shown in Fig. 4 and in full lines in Fig. 5 and from the characters in line therewith 105 on the printing-wheels *k'*, the printing-frame *s* is restored to its original position by a retracting-spring *s'*, Fig. 3, under the control of said cam *r*. Motion is then transmitted to the record-drum *o* from said shaft *n'* 110 through spur-gearing *u*, a Geneva stop movement *v*, Figs. 4 and 5, and spur-gearing *w*, connecting the star-wheel 3* of the stop movement with the drum *o*, so as to shift the record-sheet carried upon its periphery preparatory to the next printing operation, and the resetting of the trip-counter numeral-wheels *e* is then completed and the movable parts of the resetting device automatically 115 restored to the positions they occupy during 120 the registering operation, as in Figs. 3 and 4.

The resetting operation and printing operation, as above described, do not affect the position of the direction-indicator *g* or of the printing device *k*; but the operation of 125 these parts is controlled by the resetting operation and can only be effected during the resetting operation, as will now appear. The face-plate of said stop movement is constructed with a pair of concentric peripheral 130

locking-surfaces 3 and 3', Figs. 4 and 5, and a pair of peripheral notches 4 and 4' alternating therewith or following the respective locking-surfaces, the same being duplicated, 5 because this part in the construction shown makes only one-half a revolution during each resetting operation. During the registering operations when the resetting and printing mechanisms are at rest one or the other of 10 said locking-surfaces 3 and 3' is in contact with a stud 5 on a swinging lever x, which has its pivot 6 near the back of the register and carries another stud 7 at its free end, which contacts with one or the other of a 15 pair of detent-surfaces 8 and 8' on a cam y, which is fast on the protruding near end of the rock-shaft g² of the direction-indicator g and is held in contact with one or the other of said surfaces 8 and 8' by a retracting- 20 spring y', stretched from said lever y to a stud 9 on the adjacent frame-piece z, the relation of these parts being such that the direction-indicator g and printing device k, being movable together, cannot be shifted to 25 change the direction-sign and to correspondingly set the printing device while said stud 5 is in contact with either of said locking-surfaces 3 and 3'. At a given point in each 30 resetting operation, preferably immediately after the retraction of the printing-frame s after taking an impression, one or the other of said notches 4 and 4' is brought opposite said stud 5, as in Fig. 5, and the direction-indicator g and printing device k are then 35 free to be operated in the manner illustrated by this figure.

Motion is imparted to the direction-indicator g and printing device k to change the direction-sign and to bring the appropriate 40 surface 1 or 2 of the printing device into effective position by the external handle p, which is so located as to be accessible to the conductor and connected with a pitman p', extending downwardly from a wrist-pin 10 45 on said cam y on the direction-indicator rock-shaft g² to the vicinity of said butterfly-cam t on the shaft k² of said printing device k and the printing-wheels k', where it is provided with a stud 11, contacting with said 50 butterfly-cam t, as in Figs. 6 and 8. In this manner motion may be transmitted to the direction-indicator g and printing device k at will during that period of the resetting operation when they are so unlocked, but only 55 during this period, and the direction-indicator and printing device are not otherwise affected by the resetting and printing operations, which may consequently take place as often as may be desired during a given trip 60 or direction of travel. The simplest form of said external handle p is that of a depending knob with its stem attached to a rigid arm 12 of the pitman p', as indicated in Figs. 1 to 8, inclusive. An objection to this form is 65 that it exposes the shifting devices to dis-

arrangement by violence if the conductor is so disposed when the direction-indicator g and printing device k are locked. Such violence may be prevented, as illustrated by Figs. 9 and 10, by substituting for said depending handle p and rigid arm 12 a laterally-projecting rock-shaft p², having a key end external to the register-casing and connected by a slotted lever-arm 12' with the pitman p'. With either form of such external handle p the conductor can readily manipulate the resetting and printing mechanisms by his right hand applied to the key n and at the same time operate the direction-indicator g and printing device k by his left hand. 70 75 80

The indicator-spot j, Fig. 8, for indicating to the conductor the moment during which the direction-indicator g and printing device k may be shifted, is preferably and conveniently located on the bell m, so as to be exposed to view through said sight-hole j' when the resetting-key n and shaft n² have been turned to a sufficient extent to unlock the controlling-lever x, or, in other words, to 85 the extent indicated in Figs. 5 and 8. As the bell m is carried by said shaft n² and rotates therewith, it affords a convenient background for an indicating-spot of contrasting color exposed to view through a sight-hole 90 in the dial-plate, as above described, and the addition of another part for this purpose is 95 thus obviated.

The locking and unlocking device may obviously have only one locking-surface (3 or 3') and one freeing-notch (4 or 4') or more than two of each, according to the number of its rotations during each resetting operation, and other like modifications will suggest themselves to those skilled in the art. 100 105

Having thus described said improvement, I claim as my invention and desire to patent under this specification—

1. A fare-register having, in combination, a fare-counter, a set of number-printing 110 wheels, means for actuating said fare-counter and said printing-wheels, a trip-indication-printing device, means for taking impressions from said printing-wheels and said printing device at will, means distinct from the impression-taking means for shifting said printing device by hand at the end of each trip, and means distinct from the shifting means for controlling such shifting operation. 115

2. A fare-register having, in combination, a fare-counter, a set of number-printing 120 wheels, means for actuating said fare-counter and said printing-wheels, a trip-indication-printing device, means for taking impressions from said printing-wheels and said printing 125 device at will, means distinct from the impression-taking means for shifting said printing device by hand at the end of each trip, and means distinct from the shifting means for confining such shifting operation to a lim- 130

ited period after a printing operation is completed.

3. A fare-register having, in combination, a fare-counter, a set of number-printing wheels, means for actuating said fare-counter and said printing-wheels, a trip-indication-printing device, means for taking impressions from said printing-wheels and said printing device at will, normally locked means distinct from the impression-taking means for shifting said printing device by hand at the end of each trip and means for unlocking such shifting means after each printing operation.

4. A fare-register having, in combination, a fare-counter, a set of number-printing wheels, actuating means common to both, a trip-indication-printing device, means for taking impressions from said printing-wheels and said printing device at will including a record-drum, means for turning said drum after each printing operation, means distinct from the drum-turning means for shifting said printing device by hand at the end of each trip, and means for preventing such shifting operation when the drum-turning means is at rest.

5. A fare-register having, in combination, a fare-counter, a set of number-printing wheels, actuating means common to both, a trip-indication-printing device, means for taking impressions from said printing-wheels and said printing device at will including a record-drum, means for turning said drum after each printing operation, means distinct from the drum-turning means for shifting said printing device by hand at the end of each trip, and means for confining such shifting operation to a limited period after a printing operation is completed.

6. A fare-register having, in combination, a fare-counter, a set of number-printing wheels, actuating means common to both, a trip-indication-printing device, means for taking impressions from said printing-wheels and said printing device at will including a record-drum, means for turning said drum after each printing operation, normally locked means distinct from the drum-turning means for shifting said printing device by hand at the end of each trip, and means for unlocking said shifting means during each drum-turning operation.

7. A fare-register having, in combination, a fare-counter, a set of number-printing wheels, actuating means common to both, a direction-indicator and a trip-indication-printing device movable at the end of each trip, means for taking impressions from said printing-wheels and said printing device at will, means distinct from the impression-taking means for shifting said direction-indicator and said printing device by hand at the end of each trip, and means distinct from the shifting means for controlling such shifting operation.

8. A fare-register having, in combination, a fare-counter, a set of number-printing wheels, actuating means common to both, a direction-indicator and a trip-indication-printing device movable at the end of each trip, means for taking impressions from said printing-wheels and said printing device at will, means distinct from the impression-taking means for shifting said direction-indicator and said printing device by hand at the end of each trip, and means for confining such shifting operation to a limited period after a printing operation is completed.

9. A fare-register having, in combination, a fare-counter, a set of number-printing wheels, actuating means common to both, a direction-indicator and a trip-indication-printing device movable at the end of each trip, means for taking impressions from said printing-wheels and said printing device at will, normally locking means distinct from the impression-taking means for shifting said direction-indicator and said printing device by hand at the end of each trip, and means for unlocking said shifting means during a limited period after each printing operation.

10. A fare-register having, in combination, a fare-counter, a set of number-printing wheels, actuating means common to both, a trip-indication-printing device, means for taking impressions from said printing-wheels and said printing device at will, means for locking said actuating means before the beginning of each printing operation and for unlocking the same after each printing operation, means distinct from said impression-taking means for shifting said printing device by hand at the end of each trip, and means for preventing such shifting operation when the actuating means is unlocked.

11. A fare-register having, in combination, a fare-counter, a set of number-printing wheels, actuating means common to both, a trip-indication-printing device, means for taking impressions from said printing-wheels and said printing device at will, means for locking said actuating means before each printing operation and for unlocking the same after each printing operation, means distinct from said impression-taking means for shifting said printing device by hand at the end of each trip, and means for confining such shifting operation to a limited period after a printing operation is completed.

12. A fare-register having, in combination, a fare-counter, a set of number-printing wheels, actuating means common to both, a trip-indication-printing device, means for taking impressions from said printing-wheels and said printing device at will, means for locking said actuating means before each printing operation and for unlocking the same after each printing operation, normally locked means distinct from said impression-taking means for shifting said printing de-

vice by hand, and means for unlocking said shifting means during a limited period after said actuating means is locked.

13. A fare-register having, in combination, 5 a fare-counter, a set of number-printing wheels, actuating means common to both, a trip-indication-printing device, means for taking impressions from said printing-wheels and said printing device at will including a 10 key, means for shifting said printing device at the end of each trip including a handle, mean for controlling such shifting operation, a casing and dial-plate inclosing said impression taking shifting and controlling means 15 except said key and handle, and an indicator movable with said key for indicating such period during which the printing device can be shifted.

14. A fare-register having, in combination, 20 a fare-counter, a set of number-printing wheels, actuating means common to both, a trip-indication-printing device, means for taking impressions from said printing-wheels and said printing device at will including a 25 key, means distinct from the impression-taking means for shifting said printing device by hand at the end of each trip including a handle, means for controlling such shifting operation, a casing inclosing said impression 30 taking shifting and controlling means except said key and handle, an indicator within said casing movable with said key, and a dial-plate having a sight-hole exposing to view said indicator when the parts are in position for such shifting operation.

15. A fare-register having, in combination, 35 a fare-counter, a set of number-printing wheels, actuating means common to both, a trip-indication-printing device, means for taking impressions from said printing-wheels and said printing device at will including a 40 key, means for shifting said printing device at the end of each trip including a handle, means for controlling such shifting operation, 45 a casing and dial-plate inclosing said impression taking shifting and controlling means except said key and handle, a shaft movable by said key, and a part movable with said shaft provided with an indicator-spot, said 50 dial-plate having a sight-hole exposing to view said indicator-spot when the parts are in position for such shifting operation.

16. A fare-register having, in combination, 55 a fare-counter, a set of number-printing wheels, means for actuating said fare-counter and said printing-wheels, a trip-indication-printing device movable at the end of each trip, means for taking impressions from said printing-wheels and said printing device at 60 will including a key, means distinct from the impression-taking means for shifting said printing device by hand, and means for controlling this shifting operation, such controlling means including a notched part 65 movable by said key and a part movable

with said shifting means interacting with said notched part and movable only when a notch is brought into coincidence therewith.

17. A fare-register having, in combination, 70 a fare-counter, a set of number-printing wheels, means for actuating said fare-counter and said printing-wheels, a trip-indication-printing device movable at the end of each trip, means for taking impressions from said printing-wheels and said printing device at 75 will including a rotatable key, means distinct from the impression-taking means for shifting said printing device by hand, and means for controlling this shifting operation, such controlling means including a peripherally-notched disk rotatable by said key and a part 80 movable with said shifting means interacting with said disk and movable only when a notch is brought into coincidence therewith.

18. A fare-register having, in combination 85 a fare-counter, a set of number-printing wheels, means for actuating said fare-counter and said printing-wheels, a trip-indication-printing device movable at the end of each trip, means for taking impressions from said 90 printing-wheels and said printing device at will including a rotatable key, a stop movement actuated by said key, means distinct from the impression-taking means for shifting said printing device by hand, and means 95 for controlling this shifting operation, such controlling means including a peripherally-notched disk forming part of said stop movement and a part movable with said shifting means interacting with said disk and movable 100 only when a notch is brought into coincidence therewith.

19. A fare-register having, in combination, 105 a trip-counter adapted to be reset to zero at will, a set of number-printing wheels, means for actuating said trip-counter and said printing-wheels, means for resetting said trip-counter, a trip-indication-printing device, means for taking impressions from said printing-wheels and said printing device at each 110 resetting operation, means distinct from the resetting means for shifting said printing device by hand at the end of each trip, and means for preventing such shifting operation when the trip-counter-resetting means is at 115 rest.

20. A fare-register having, in combination, 120 a trip-counter adapted to be reset to zero at will, a set of number-printing wheels, means for actuating said trip-counter and said printing-wheels, means for resetting said trip-counter, a trip-indication-printing device, means for taking impressions from said printing-wheels and said printing device at each 125 resetting operation, means distinct from the resetting means for shifting said printing device by hand at the end of each trip, and means for confining such shifting operation to a limited period after a printing operation is completed.

21. A fare-register having, in combination, a trip-counter adapted to be reset to zero at will, a set of number-printing wheels, means for actuating said trip-counter and said printing-wheels, means for resetting said trip-counter, a trip-indication-printing device, means for taking impressions from said printing-wheels and said printing device at each resetting operation, normally locked means distinct from the resetting means for shifting said printing device by hand at the end of each trip, and means for unlocking said shifting means during each resetting operation.

22. A fare-register having, in combination, a trip-counter adapted to be reset to zero at will, a set of number-printing wheels, actuating means common to both, means for resetting said trip-counter, a trip-indication-printing device, means for taking impressions from said printing-wheels and said printing device including a record-drum, means for turning said drum after each printing operation, means distinct from the resetting means for shifting said printing device by hand at the end of each trip, and means for preventing such shifting operation when the trip-counter-resetting means is at rest.

23. A fare-register having, in combination, a trip-counter adapted to be reset to zero at will, a set of number-printing wheels, actuating means common to both, means for resetting said trip-counter, a trip-indication-printing device, means for taking impressions from said printing-wheels and said printing device including a record-drum, means for turning said drum after each printing operation, means distinct from the resetting means for shifting said printing device by hand at the end of each trip, and means for confining such shifting operation to a limited period after a printing operation is completed.

24. A fare-register having, in combination, a trip-counter, adapted to be reset to zero at will, a set of number-printing wheels, actuating means common to both, means for resetting said trip-counter, a trip-indication-printing device, means for taking impressions from said printing-wheels and said printing device including a record-drum, means for turning said drum after each printing operation, normally locked means distinct from the resetting means for shifting said printing device by hand at the end of each trip, and means for unlocking said shifting means during each resetting operation.

25. A fare-register having, in combination, a trip-counter adapted to be reset to zero at will, a set of number-printing wheels, means for actuating said trip-counter and said printing-wheels, means for resetting said trip-counter, a direction-indicator movable at the end of each trip, a trip-indication-printing device movable with said direction-indicator, means for taking impressions from said printing device at each resetting operation, normally locked means distinct from the resetting means for shifting said direction-indicator and said printing device by hand, and means for preventing such shifting operation when the trip-counter-resetting means is at rest.

26. A fare-register having, in combination, a trip-counter adapted to be reset to zero at will, a set of number-printing wheels, means for actuating said trip-counter and said printing-wheels, means for resetting said trip-counter, a direction-indicator movable at the end of each trip, a trip-indication-printing device movable at the end of each trip, means for taking impressions from said printing-wheels and said printing device at each trip-counter-resetting operation, means distinct from the resetting means for shifting said direction-indicator and said printing device by hand, and means for confining such shifting operation to a limited period after a printing operation is completed.

27. A fare-register having, in combination, a trip-counter adapted to be reset to zero at will, a set of number-printing wheels, means for actuating said trip-counter and said printing-wheels, means for resetting said trip-counter, a direction-indicator movable at the end of each trip, a trip-indication-printing device movable with said direction-indicator at each trip-counter-resetting operation, normally locked means distinct from the resetting means for shifting said direction-indicator and said printing device by hand, and means for unlocking said shifting means during each resetting operation.

28. A fare-register having, in combination, a trip-counter adapted to be reset to zero at will, a set of number-printing wheels, actuating means common to both, means for resetting said trip-counter, means for locking said actuating means at the beginning of each resetting operation and for unlocking the same at the end of each resetting operation, a trip-indication-printing device, means for taking impressions from said printing-wheels and said printing device, means distinct from the resetting means for shifting said printing device by hand at the end of each trip, and means for preventing such shifting operation when the resetting means is at rest.

29. A fare-register having, in combination, a trip-counter adapted to be reset to zero at will, a set of number-printing wheels, actuating means common to both, means for resetting said trip-counter, means for locking said actuating means at the beginning of each resetting operation and for unlocking the same at the end of each resetting operation, a trip-indication-printing device, means for taking impressions from said printing-wheels and said printing device, means distinct from the resetting means for shifting said printing device by hand at the end of each trip, and

means for confining such shifting operation to a limited period after a printing operation is completed.

30. A fare-register having, in combination, 5 a trip-counter adapted to be reset to zero at will, a set of number-printing wheels, actuating means common to both, means for resetting said trip-counter, means for locking said actuating means at the beginning of each 10 resetting operation and for unlocking the same at the end of each resetting operation, a trip-indication-printing device, means for taking impressions from said printing-wheels and said printing device, normally locked 15 means distinct from the resetting means for shifting said printing device by hand at the end of each trip, and means for unlocking said shifting means during a limited period after said actuating means is locked.
- 20 31. A fare-register having, in combination, a trip-counter adapted to be reset to zero at will, a set of number-printing wheels, actuating means common to both, means for resetting said trip-counter including a key, a trip-indication-printing device, means for taking 25 impressions from said printing-wheels and said printing device, means distinct from the resetting means for shifting said printing device by hand at the end of each trip including 30 a handle, means for preventing such shifting operation when the trip-counter-resetting means is at rest, a casing and dial-plate inclosing said resetting, shifting and preventing means, except said key and handle, and 35 an indicator movable with said resetting means for indicating the period during which the printing device can be shifted.

32. A fare-register having, in combination, a trip-counter adapted to be reset to zero at 40 will, a set of number-printing wheels, actuating means common to both, means for resetting said trip-counter including a key, a trip-indication-printing device, means for taking impressions from said printing-wheels and 45 said printing device, means distinct from the resetting means for shifting said printing device by hand at the end of each trip including a handle, means for preventing such shifting operation when the trip-counter-resetting 50 means is at rest, a casing and dial-plate inclosing said resetting, shifting and preventing means, except said key and handle, and an indicator within said casing movable with said resetting means, said dial-plate having 55 a sight-hole exposing to view said indicator when the parts are in position for such shifting operation.

33. A fare-register having, in combination, a trip-counter adapted to be reset to zero at 60 will, a set of number-printing wheels, actuating means common to both, means for resetting said trip-counter to zero including a key, a trip-indication-printing device, means for taking impressions from said printing-wheels and said printing device, means distinct from

the resetting means for shifting said printing device by hand at the end of each trip including a handle, means for preventing such shifting operation when the trip-counter-resetting means is at rest, a casing and dial-plate inclosing said resetting, shifting and preventing means, except said key and handle, a shaft movable by said key, and a part movable with said shaft provided with an indicator-spot, said dial-plate being provided 70 with a sight-hole exposing to view said indicator-spot when the parts are in position for such shifting operation. 75

34. A fare-register having, in combination, a trip-counter adapted to be reset to zero at 80 will, a set of number-printing wheels, means for actuating said trip-counter and said printing-wheels, means for resetting said trip-counter including a key, a trip-indication-printing device, means for taking impressions 85 from said printing-wheels and said printing device at each trip-counter-resetting operation, means distinct from the resetting means for shifting said printing device by hand at the end of each trip, and means for preventing 90 such shifting operation when the trip-counter-resetting means is at rest, such preventing means including a notched part movable by said key and a part movable with said shifting means interacting with 95 said notched part and movable only when a notch is moved into coincidence therewith.

35. A fare-register having, in combination, a trip-counter adapted to be reset to zero at will, a set of number-printing wheels, means 100 for resetting said trip-counter including a rotatable key, a trip-indication-printing device, means for taking impressions from said printing-wheel and said printing device at each trip-counter-resetting operation, means distinct from the resetting means for shifting said printing device by hand at the end of each trip, and means for preventing such shifting operation when the trip-counter-resetting means is at rest, such preventing 105 means including a peripherally-notched disk rotatable by said key, and a part movable with said shifting means interacting with said disk and movable only when a peripheral notch is moved into coincidence therewith. 110

36. A fare-register having, in combination, a trip-counter adapted to be reset to zero at will, a set of number-printing wheels, means for resetting said trip-counter including a rotatable key, a trip-indication-printing device, 120 means for taking impressions from said printing-wheel and said printing device at each trip-counter-resetting operation, a stop-movement actuated by said key, means distinct from the resetting means for shifting 125 said printing device by hand at the end of each trip, and means for preventing such shifting operation when the trip-counter-resetting means is at rest, such preventing means including a peripherally-notched disk 130

forming part of said stop-movement and a part movable with said shifting means interacting with said disk and movable only when a peripheral notch is moved into coincidence therewith.

37. A fare-register having, in combination, a trip-counter adapted to be reset to zero at will, a totalizer, a set of number-printing wheels, means for actuating said trip-counter totalizer and printing-wheels, means for resetting said trip-counter, a trip-indication-printing device, means for taking impressions from said printing-wheels and said printing device at each resetting operation, means distinct from the resetting means for shifting said printing device by hand at the end of each trip, and means for preventing such shifting operation when the trip-counter-resetting means is at rest.
38. A fare-register having, in combination, a trip-counter adapted to be reset to zero at will, a totalizer, a set of number-printing wheels, means for actuating said trip-counter totalizer and printing-wheels, means for resetting said trip-counter, a trip-indication-printing device, means for taking impressions from said printing-wheels and said printing device at each resetting operation, means distinct from the resetting means for shifting said printing device by hand at the end of each trip, and means for confining such shifting operation to a limited period after a printing operation is completed.
39. A fare-register having, in combination, a trip-counter adapted to be reset to zero at will, a totalizer, a set of number-printing wheels, means for actuating said trip-counter totalizer and printing-wheels, means for resetting said trip-counter, a trip-indication-printing device, means for taking impressions from said printing-wheels and said printing device at each resetting operation, normally locked means distinct from the resetting means for shifting said printing device by hand at the end of each trip, and means for unlocking said shifting means during each resetting operation.
40. A fare-register having, in combination, a trip-counter adapted to be reset to zero at will, a totalizer, a set of number-printing wheels, means for actuating said trip-counter totalizer and printing-wheels, a trip-indication-printing device, means for resetting said trip-counter and for taking impressions from said printing-wheels and said printing device including a record-drum, means for turning said drum after each printing operation, means distinct from the resetting means for shifting said printing device by hand at the end of each trip, and means for preventing such shifting operation when the trip-counter-resetting means is at rest.

41. A fare-register having, in combination, a trip-counter adapted to be reset to zero at will, a totalizer, a set of number-printing

wheels, means for actuating said trip-counter totalizer and printing-wheels, a trip-indication-printing device, means for resetting said trip-counter and for taking impressions from said printing-wheels and said printing device including a record-drum, means for turning said drum after each printing operation, means distinct from the resetting means for shifting said printing device by hand at the end of each trip, and means for confining such shifting operation to a limited period after a printing operation is completed.

42. A fare-register having, in combination, a trip-counter adapted to be reset to zero at will, a totalizer, a set of number-printing wheels, means for actuating said trip-counter totalizer and printing-wheels, a trip-indication-printing device, means for resetting said trip-counter and for taking impressions from said printing-wheels and said printing device including a record-drum, means for turning said drum after each printing operation, normally locked means distinct from the resetting means for shifting said printing device by hand at the end of each trip, and means for unlocking such shifting means during each resetting operation.

43. A fare-register having, in combination, a trip-counter adapted to be reset to zero at will, a totalizer, a set of number-printing wheels, means for actuating said trip-counter totalizer and printing-wheels, means for resetting said trip-counter to zero, a direction-indicator and a trip-indication-printing device movable in unison, means for taking impressions from said printing-wheels and said printing device at each resetting operation, means distinct from the resetting means for shifting said direction-indicator and said printing device by hand at the end of each trip, and means for preventing such shifting operation when the trip-counter-resetting means is at rest.

44. A fare-register having, in combination, a trip-counter adapted to be reset to zero at will, a totalizer, a set of number-printing wheels, means for actuating said trip-counter totalizer and printing-wheels, means for resetting said trip-counter to zero, a direction-indicator and a trip-indication-printing device movable in unison, means for taking impressions from said printing-wheels and said printing device at each resetting operation, means distinct from the resetting means for shifting said direction-indicator and said printing device by hand at the end of each trip, and means for confining such shifting operation to a limited period after a printing operation is completed.

45. A fare-register having, in combination, a trip-counter adapted to be reset to zero at will, a totalizer, a set of number-printing wheels, means for actuating said trip-counter totalizer and printing-wheels, means for resetting said trip-counter to zero, a direction-

indicator and a trip-indication-printing device movable in unison, means for taking impressions from said printing-wheels and said printing device at each resetting operation, 5 normally locked means distinct from the resetting means for shifting said direction-indicator and said printing device by hand at the end of each trip, and means for unlocking said shifting means during each resetting operation.

46. A fare-register having, in combination, a trip-counter adapted to be reset to zero at will, a totalizer, a set of number-printing wheels, means for simultaneously actuating said trip-counter totalizer and printing-wheels, means for resetting said trip-counter, means for locking said actuating means at the beginning of each resetting operation and for unlocking the same at the end of each resetting operation, a trip-indication-printing device, means for taking impressions from said printing-wheels and said printing device at each resetting operation, means distinct from the resetting means for shifting said printing device by hand at the end of each trip, and means for preventing such shifting operation when the trip-counter-resetting means is at rest.

47. A fare-register having, in combination, a trip-counter adapted to be reset to zero at will, a totalizer, a set of number-printing wheels, means for simultaneously actuating said trip-counter totalizer and printing-wheels, means for resetting said trip-counter, 35 means for locking said actuating means at the beginning of each resetting operation and for unlocking the same at end of each resetting operation, a trip-indication-printing device, means for taking impressions from said printing-wheels and said printing device at each resetting operation, means distinct from the resetting means for shifting said printing device by hand at the end of each trip, and means for confining such shifting operation 45 to a limited period after a printing operation is completed.

48. A fare-register having, in combination, a trip-counter adapted to be reset to zero at will, a totalizer, a set of number-printing wheels, means for simultaneously actuating said trip counter totalizer and printing-wheels, means for resetting said trip-counter, means for locking said actuating means at the beginning of each resetting operation and for 55 unlocking the same at the end of each resetting operation, a direction-indicator and a trip-indication-printing device movable in unison, means for taking impressions from said printing-wheels and said printing device 6c at each resetting operation, normally locked means distinct from the resetting means for shifting said direction-indicator and said printing device by hand at the end of each trip, and means for unlocking said shifting means 65 during a limited period after said actuating

means is locked and before the same is unlocked.

49. A fare-register having, in combination, a trip-counter adapted to be reset to zero at will, a totalizer, a set of number-printing 70 wheels, means for actuating said trip-counter totalizer and printing-wheels, a trip-indication-printing device, means for resetting said trip-counter and for taking impressions from said printing-wheels and said printing 75 device including a key, means for shifting said printing device at the end of each trip including a handle, means for preventing such shifting operation when the trip-counter-resetting means is at rest, a casing and dial-plate inclosing said resetting shifting and preventing means except said key and handle, and an indicator movable with said key for indicating the period during which the printing device can be shifted. 80

50. A fare-register having, in combination, a trip-counter adapted to be reset to zero at will, a totalizer, a set of number-printing wheels, means for actuating said trip-counter totalizer and printing-wheels, a trip-indication-printing device, means for resetting said 90 trip-counter and for taking impressions from said printing-wheels and said printing device including a key, means for shifting said printing device at the end of each trip including a 95 handle, means for preventing such shifting operation when the trip-counter-resetting means is at rest, a casing and dial-plate inclosing said resetting shifting and preventing means except said key and handle, an indicator within said casing movable with said key, and a dial-plate having a sight-hole exposing to view said indicator when the parts are in position for such shifting operation. 100

51. A fare-register having, in combination, a trip-counter adapted to be reset to zero at will, a totalizer, a set of number-printing wheels, means for actuating said trip-counter totalizer and printing-wheels, a trip-indication-printing device, means for resetting said 105 trip-counter and for taking impressions from said printing-wheels and said printing device including a key, means for shifting said printing device at the end of each trip including a handle, means for preventing such shifting 115 operation when the trip-counter-resetting means is at rest, a casing and dial-plate inclosing said resetting shifting and preventing means except said key and handle, a shaft movable by said key, and a part movable with 120 said shaft provided with an indicator-spot, said dial-plate being provided with a sight-hole exposing to view said indicator-spot when the parts are in position for such shifting operation. 125

52. A fare-register having, in combination, a trip-counter adapted to be reset to zero at will, a totalizer, a set of number-printing wheels, means for actuating said trip-counter totalizer and printing-wheels, means for re- 130

setting said trip-counter including a key, a trip-indication-printing device, means for taking impressions from said printing-wheels and said printing device at each trip-counter- 5 resetting operation, means distinct from the resetting means for shifting said printing device by hand at the end of each trip, and means for preventing such shifting operation when the trip-counter-resetting means is at 10 rest, such preventing means including a notched part movable by said key and a part movable with said shifting means interacting with said notched part and movable only when a notch is moved into coincidence 15 therewith.

53. A fare-register having, in combination, a trip-counter adapted to be reset to zero at will, a totalizer, a set of number-printing wheels, means for actuating said trip-counter 20 totalizer and printing wheels, means for resetting said trip-counter including a rotatable key, a trip-indication-printing device, means for taking impressions from said printing-wheel and said printing device at each 25 trip-counter-resetting operation, means distinct from the resetting means for shifting said printing device by hand at the end of each trip, and means for preventing such shifting operation when the trip-counter- 30 resetting means is at rest, such preventing means including a peripherally-notched disk rotatable by said key and a part movable with said shifting means interacting with said disk and movable only when a peripheral notch is moved into coincidence therewith. 35

54. A fare-register having, in combination, a trip-counter adapted to be reset to zero at will, a totalizer, a set of number-printing 40 wheels, means for actuating said trip-counter totalizer and printing wheels, means for resetting said trip-counter including a rotatable key, a trip-indication-printing device, means for taking impressions from said printing-wheel and said printing device at each 45 trip - counter - resetting operation, a stop movement actuated by said key, means distinct from the resetting means for shifting said printing device by hand at the end of each trip, and means for preventing such 50 shifting operation when said resetting means is at rest, such preventing means including a peripherally-notched disk forming part of said stop movement and a part movable with 55 said stiffening means interacting with said disk and movable only when a peripheral notch is moved into coincidence therewith.

55. The combination, in a fare-register, of a trip-indication-printing device, means for 60 manually shifting said printing device at the end of each trip and means for controlling such shifting operation including a movable part having a locking-surface and a notch, means for moving said part, a lever carrying a 65 stud arranged to interact with said locking-

surface and said notch and a cam movable with said shifting device and adapted to interact with said lever, the construction of these parts being such that when said stud and said locking-surface are in contact said 70 lever is locked against movement by said cam and when said notch is moved into coincidence with said stud said lever is unlocked for the shifting operation.

56. The combination, in a fare-register, of 75 a trip-indication-printing device, means for manually shifting said printing device at the end of each trip, and means for controlling such shifting operation including a rotatable disk having a peripheral locking-surface and 80 a peripheral notch, means for rotating said disk, a lever carrying a stud to interact with said locking-surface and said notch and a cam movable with the shifting device and adapted to interact with said lever, the construction of these parts being such that when 85 said stud and said locking-surface are in contact said lever is locked against movement by said cam and when said notch is moved into coincidence with said stud said lever is 90 unlocked for the shifting operation.

57. The combination, in a fare-register, of 95 a trip-indication-printing device, means for manually shifting said printing device at the end of each trip, and means for controlling such shifting operation including a rotatable disk having peripheral locking-surfaces each 100 followed by a peripheral notch, means for rotating said disk, a lever carrying a stud arranged to interact with said locking-surfaces and said notches and a cam movable with said shifting device and adapted to interact with said lever, the construction of these parts being such that when said stud and either of said locking-surfaces are in contact 105 said lever is locked against movement by said cam and when either of said notches is moved into coincidence with said stud said lever is unlocked for the shifting operation.

58. The combination, in a fare-register, of 100 a direction-indicator, means for manually shifting the same at the end of each trip and means for controlling such shifting operation including a movable part having a locking-surface and a notch, means for moving said 115 part, a lever carrying a stud arranged to interact with said locking-surface and said notch and a cam movable with said direction indicator and adapted to interact with said lever, the construction of these parts being 120 such that when said stud and locking-surface are in contact said lever is locked against movement by said cam and when said notch is moved into coincidence with said stud said lever is unlocked for the shifting operation. 125

59. The combination, in a fare-register, of 130 a direction-indicator, means for manually shifting the same at the end of each trip, and means for controlling such shifting operation including a rotatable disk having a periph-

eral locking-surface and a peripheral notch, means for rotating said disk, a lever carrying a stud arranged to interact with said locking-surface and said notch and a cam movable 5 with said direction-indicator and adapted to interact with said lever, the construction of these parts being such that when said stud and said locking-surface are in contact said lever is locked against movement by said cam 10 and when said notch is moved into coincidence with said stud said lever is unlocked for the shifting operation.

60. The combination, in a fare-register, of a direction-indicator movable on a horizontal rock-shaft, means for manually shifting said direction-indicator at the end of each trip, and means for controlling such shifting operation including a rotatable disk having peripheral locking-surfaces each followed by 15 a peripheral notch, means for rotating said disk, a lever carrying a stud arranged to interact with said locking-surfaces and said notches and a cam movable with said rock-shaft and adapted to interact with said lever, 20 the construction of these parts being such that when said stud and either of said locking-surfaces are in contact said lever is locked against movement by said cam and when either of said notches is moved into coincidence with said stud said lever is unlocked for the shifting operation.

61. The combination, in a fare-register, of a direction-indicator, a trip-indication printing device, means for manually shifting said 25 direction-indicator and said printing device at the end of each trip, and means for controlling such shifting operation including a movable part having a locking-surface and a notch, means for moving said part, a lever 30 carrying a stud arranged to interact with said locking-surface and said notch, and a cam movable with said direction-indicator and adapted to interact with said lever, the construction of these parts being such that when 35 said stud and said locking-surface are in contact said lever is locked against movement

by said cam and when said notch is moved into coincidence with said stud said lever is unlocked for the shifting operation.

62. The combination, in a fare-register, of 50 a direction-indicator and a trip-indication-printing device, means for manually shifting said direction-indicator and said printing device at the end of each trip, and means for controlling such shifting operation including a rotatable disk having a peripheral locking-surface and a peripheral notch, means for rotating said disk, a lever carrying a stud arranged to interact with said locking-surface and said notch, and a cam movable with said 55 direction-indicator and adapted to interact with said lever, the construction of these parts being such that when said stud and said locking-surface are in contact said lever is locked against movement by said cam and when said notch is moved into coincidence with said stud said lever is unlocked for the shifting operation.

63. The combination, in a fare-register, of a direction-indicator, a trip-indication-printing device, means for manually shifting said direction-indicator and said printing device at the end of each trip, and means for controlling such shifting operation including a rotatable disk having peripheral locking-surfaces each followed by a peripheral notch, 70 means for rotating said disk, a lever carrying a stud arranged to interact with said locking-surfaces and said notches and a cam movable with said direction-indicator and adapted to interact with said lever; the construction of these parts being such that when said stud and either of said locking-surfaces are in contact said lever is locked against movement by said cam and when either of said notches is moved into coincidence with said stud said lever is unlocked for the shifting operation, 75 substantially as hereinbefore specified.
